POWER UNIT FOR HYDRAULIC ELEVATORS

James H. Bartholomew, Greensboro, N.C., assignor to
Monarch Elevator & Machine Co., Inc., Greensboro,
N.C.

Filed Dec. 19, 1956, Ser. No. 44,254

Term of patent 14 years

(Cl. D55—1)

Fig. 1 is a front elevational view of a power unit for hydraulic elevators, showing my new design;

Fig. 2 is a top plan view; and

Fig. 3 is a rear elevational view thereof.

I claim:

The ornamental design for a power unit for hydraulic elevators, as shown.
